UNITED STATES PATENT OFFICE

155,853

DESIGN FOR A THERMOMETER

Ralph C. Wappner, Springfield, Ohio, assignor to
The Ohio Thermometer Co., Inc., Springfield,
Ohio, a corporation of Ohio

Application May 15, 1947, Serial No. 139,048

Term of patent 7 years

(Cl. D52—7)

To all whom it may concern:

Be it known that I, Ralph C. Wappner, a citizen of the United States and a resident of Springfield, in the county of Clark and State of Ohio, have invented a new, original, and ornamental Design for a Thermometer, of which the following is the specification, reference being had to the accompanying drawings, forming a part thereof, wherein:

Figure 1 is a front elevation of a thermometer, showing my new design;

Figure 2 is a rear view thereof;

Figure 3 is a side view;

Figure 4 is a view looking down from the top; and

Figure 5 is a sectional view taken along line 5—5 of Figure 3 showing the arrangement of the parts within the thermometer.

The characteristic features of my design reside in the specific shape and arrangement of the brackets and end caps, and in the triangular support for the thermometer tube, all as illustrated.

I claim:

The ornamental design for a thermometer, substantially as shown and described.

R. C. WAPPNER.
